REEL CARRIER

Gerald A. M. Petersen, Santa Clara, Robert W. Goode,
Morgan Hill, and Robert W. Selleck, San Jose, Calif.;
said Goode and said Selleck assignors to said Petersen

Application July 20, 1956, Serial No. 42,323

Term of patent 14 years

(Cl. D14—3)

The figure is a perspective view of a reel carrier embodying our new design, as seen from a side front position, the opposite side being like that shown in this view.

We claim:

The ornamental design for a reel carrier, as shown and described.
